Patented Aug. 12, 1969

214,958

COMBINED MOTION PICTURE PROJECTOR AND COVER

Bernard A. Barke, Sunnyvale, Calif., and Anastasios J. Vasilatos, Chicago, Ill., assignors to Bell & Howell Company, Chicago, Ill., a corporation of Illinois

Filed Apr. 18, 1968, Ser. No. 11,520

Term of patent 14 years

Int. Cl. D16—04

U.S. Cl. D61—1

Fig. 1.

Fig. 2.

Fig. 3.

FIG. 1 is a rear and side perspective view of a combined motion picture projector and cover showing my new design; and

FIG. 2 is a perspective view of FIG. 1 with the cover removed and adapted to receive a film cartridge; and

FIG. 3 is a front perspective view of FIG. 1.

Portions of the figures are diagonally lined to indicate transparency.

We claim:

The ornamental design for a combined motion picture projector and cover, as shown and described.
